UNITED STATES PATENT OFFICE.

JOHN M. OAKLEY, OF BROOKLYN, NEW YORK.

REVERSING-GEARING FOR WASHING-MACHINES.

SPECIFICATION forming part of Letters Patent No. 400,246, dated March 26, 1889.

Application filed February 10, 1887. Serial No. 227,201. (No model.)

To all whom it may concern:

Be it known that I, JOHN M. OAKLEY, a citizen of the United States, residing at Brooklyn, in the county of Kings and State of New York, have invented a new and useful Improvement in Reversing-Gearing for Washing-Machines and for other Purposes, of which the following is a full, clear, and exact description, reference being had to the accompanying drawings, forming a part of this specification.

My invention relates to improvements in that class of gearing to be applied to washing-machines in which a stationary shell and an inner revolving cylinder are used, whereby the inside cylinder is made to revolve in opposite directions automatically and alternately, as will be more fully described hereinafter.

The object of my invention is to produce a cheap, simple, and durable device, whereby the inside cylinder of a washing-machine or an agitating-machine is made to revolve in opposite directions automatically and alternately or continuously, and with suitable gears and levers starting, stopping, and locking devices and one that can be operated by unskilled labor.

Figure 1 is a side view or elevation of the reversing mechanism, also an end section of the inside and outside cylinders with shaft and gear-wheel. Fig. 2 is an end elevation of the iron frame. Fig. 3 is a view of the top of the frame and the belt-shifting bar. Fig. 4 is a detail elevation and partial section of the reciprocating bar I and some of its connections. Fig. 5 is a detail plan view, on a reduced scale, showing the connections between the cylinder-shaft and the pulley-shaft.

A, Fig. 1, represents a section of the outer casing or tank, in which is contained the revolving or inside cylinder, B, both being constructed of wood or other suitable material. The shaft C', to which the cylinder B is attached, is shown back of and at one side of the shaft F. The cylinder-shaft and casing are of any usual and well-known constructions and need not be specially described. A gear-wheel, C, is firmly keyed to the journal-shaft c', Fig. 1, and meshes with a pinion, D,

keyed to the pulley-shaft F, by which means the cylinder B is caused to revolve, as more fully described hereinafter.

E is an iron frame made of one or more pieces of metal with journal and bolt holes through it, and with means to attach it firmly to the end of the casing A, and of sufficient strength to support the pulley-shaft and other gearing, as shown in Figs. 1 and 2.

F is the pulley-shaft, which is journaled into and revolves in the frame E. At or near one end of this shaft and within the frame is the pinion D, firmly keyed to it. At the opposite end is a worm or screw, D'. This worm is made on the shaft F, the object of which is described hereinafter. Near the center of the shaft F are the pulley or belt wheels G, G', and G². The pulley-wheel G has less face surface than the pulley-wheels G' and G², and it is firmly keyed to the shaft F. On opposite sides of the pulley G are the two idlers or loose pulleys G' and G², which turn freely on the shaft.

H is a wheel meshing into and operated by the screw or worm D' on the shaft F. This wheel revolves on a short shaft, H', running at right angles to the shaft F, and is supported in the frame E, as shown in Figs. 1 and 2. On one side of the wheel H, between the hub and the outer edge, is a pin or projection extending out one inch, more or less, as shown at H², Figs. 1 and 4, the object being described hereinafter.

I is a flat metal lever or bar operated by the pin or projection on the wheel H. This lever or bar is enlarged at one end, and has a slotted or oblong opening through it, as shown at I', Figs. 1 and 4. At or near the opposite end it has two small slotted openings, as shown in Fig. 4. The object of the slotted opening in the large end is to allow it to pass over the short shaft H', holding and guiding it between the wheel H and frame E. The object of the two small slotted openings is to attach and adjust two pieces of metal, I² and I³, by means of bolts or rivets, to the bar I, to regulate its length of stroke and motion. These pieces extend a short distance below the bar, and are separated from each other one inch, more or less, as shown in Fig. 4. On one side of the bar I, at the enlarged end, are

two projections extending out from the side of the bar one inch, more or less, one being above the slotted opening and the other below it and near opposite ends of the slotted opening, as shown at I^4 and I^5 , Fig. 4.

J is an operating-lever connected at the lower end by a movable joint to the frame E near the hub or bearing of the main shaft F , as shown at J' , Fig. 1. This lever extends up to and above the top of the frame E and locks into the belt-shifting bar, described hereinafter. Near the center of the lever J a pin projects out one inch, more or less, as shown at J^2 , Figs. 1 and 4.

K is a weighted lever, pivoted in the bearing K^3 and having a ball or weight on the top, and with two arms, K^4 and K^5 , rising upward and outward. The outward end of one arm has a lug or stop, K^6 . The object is to lock the belt-shifting bar by pressing the lug K^6 into a slot in the top of the belt-shifting bar, as shown at K' , Figs. 1 and 3. At the outer end of the other arm is a pin. To this pin on arm K^4 a link, O , having a slotted opening near the top, is connected. Said lever is connected at the bottom by a movable joint to the bar I , as shown at K^2 , Figs. 1 and 4. The weighted lever K is placed between two eye-pieces east on the top of the frame E , as shown at K^3 , Figs. 1 and 3, and held in position by any suitable means. The top of the frame E is made flat, and it has two guides, $L L$, above the top. On the top of the flat part of the frame is a moving bar, M , held in place by the guides $L L$, under which said bar M moves when connected to the lever J , as hereinafter described. On the top of the moving bar M are two eye-pieces, m' and m^2 , at a suitable distance apart. Through each of these eye-pieces is passed a bar or rod having a belt-shifter, N and N' , which engage the belts in the ordinary way. These bars or rods are adjusted by a set-screw, m^3 m^3 , in the top of the eye-piece. At one side of the moving bar M , near one end, is a recess, P , into which the lever J locks. On the upper side of the moving bar M , near one end, is a rising bead or projection, P' , with a groove, K' , across it, into which the right-angled piece on the weighted lever K drops when the lever is thrown back toward the machine, thus stopping and locking the machine, said groove K' being shown in Figs. 1 and 3.

All the various parts of the gearing and levers herein described are made of iron or steel or other suitable material.

To operate my invention I employ two belts,

R and R' , as shown by the dotted lines in Fig. 1, which belts are driven by appropriate shafting and pulleys in such a manner that the belt R travels in the direction indicated by the arrow on its surface, and the belt R' travels in an opposite direction, as indicated by its arrow. Should both of these belts be driven by the same shaft, one of them must be crossed in order to obtain this opposite motion. The belts are caused to remain on the idlers or loose pulleys G' and G^2 by being passed through the oval or U -shaped rings N and N' , connected to the moving bar M , said bar being held in position by the guides $L L$ on the top of the frame E , under which it moves. To start the machine, the belts having been properly adjusted, the weighted lever K is thrown forward, thus releasing the moving bar M and allowing the lever or bar I to drop down on the pin or projection J^2 , near the center of the operating-lever J , this pin acting between the adjusting-pieces I^2 and I^3 . The wheel H is revolved by the worm or screw, the pin or projection H^2 on the side of the wheel H acting against the pins or projections I^4 and I^5 on the side of the lever or bar I . A back and forward motion is given to the bar I every revolution of the wheel H . This motion is imparted to the moving bar M by the operating-lever J , thus shifting the belts on the pulleys and giving the requisite reversing motion to the inside cylinder.

Having fully described my invention, what I desire to claim and secure by Letters Patent is—

1. The lever or bar I , having slotted openings therein, and projections, as I^4 I^5 , and adjusting-pieces I^2 I^3 thereon, in combination with the operating-lever J , belt-shifting bar M , and frame E , substantially as described.

2. The weighted lever K , the frame E , link or bar O , and slotted bar I , all in combination, as set forth.

3. The wheel H , having pin H^2 , in combination with the shaft F , having worm D' , bar I , having projections I^4 and I^5 , link O , lever J , having pin J^2 , and weighted lever K , substantially as set forth.

4. The combination of the bar I , having projections I^4 I^5 , wheel H , having pin H^2 , lever J , having pin J^2 , lever K , bar M , frame E , shaft F , worm D' , pulleys G G' G^2 , and pinion D , substantially as set forth.

JOHN M. OAKLEY.
